US00D996922S

(12) **United States Design Patent** (10) **Patent No.:** **US D996,922 S**
Ou (45) **Date of Patent:** **** Aug. 29, 2023**

(54) **DUMPLING WRAPPING MACHINE**

(71) Applicant: **Qinpingle Ou**, Chongqing (CN)

(72) Inventor: **Qinpingle Ou**, Chongqing (CN)

(**) Term: **15 Years**

(21) Appl. No.: **29/888,605**

(22) Filed: **Apr. 3, 2023**

(30) **Foreign Application Priority Data**

Feb. 17, 2023 (CN) 202330057255.1

(51) **LOC (14) Cl.** **07-04**

(57) **CLAIM**

The ornamental design for a dumpling wrapping machine, as shown and described.

DESCRIPTION

FIG. 1 is a front, right and bottom perspective view of a dumpling wrapping machine, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a cross-sectional view of the dumpling wrapping machine of FIG. 1, taken along section line 8-8 as depicted in FIG. 2.

1 Claim, 8 Drawing Sheets
